UNITED STATES PATENT OFFICE.

EMIL E. HANSEN, OF CHICAGO, ILLINOIS.

ATTACHMENT FOR SPRINKLERS.

1,071,520.

Specification of Letters Patent. Patented Aug. 26, 1913.

Application filed October 7, 1912. Serial No. 724,323.

To all whom it may concern:

Be it known that I, EMIL E. HANSEN, a former subject of the King of Denmark, who has declared his intention of becoming a citizen of the United States, and a resident of the city of Chicago, county of Cook, and State of Illinois, have invented certain new and useful Improvements in Attachments for Sprinklers, of which the following is a specification.

My invention relates to attachments for sprinklers and the object of my improvement is to provide a simple spray deflecting lip for use with conventional sprinklers for deflecting a portion of the spray delivered by such sprinkler from its regular or ordinary direction so that the sprinkler may be placed by the side of a walk and such deflecting lip prevent the spray from falling on such walk. A further object is to provide a device of this character which will be simple of construction and efficient in its operation. Other objects will appear hereinafter.

The invention consists in the combinations and arrangements of parts hereinabove described and claimed.

The invention will be best understood by reference to the accompanying drawings, and in which—

Figure 1 is a plan view of a conventional sprinkler equipped with my invention, Fig. 2 is a section of the same taken on line 2—2 in Fig. 1, Fig. 3 is a fragmental section taken on line 3—3 in Fig. 1, and Fig. 4 is a view, in perspective, of the spring member for securing the deflecting lip in operative position on the sprinkler head.

The preferred form of construction as illustrated in the accompanying drawings, comprises a conventional sprinkler head 5 having a supporting base 6 and hose connection 7 this sprinkler being of any desired construction. The sprinkler head portion 2 in the sprinkler shown is cylindrical. A deflecting lip 8 is provided with its lower portion 8' of a shape to conform with the periphery of the sprinkler head, as clearly illustrated. Such lip 8 is provided with an ear 9 and the ear 9 is slidably mounted on an angularly shaped rod 10 which is carried in the base portion 6 of the sprinkler. The rod 10 is provided with a head 11 to prevent the ear 9 from sliding off such rod. The purpose of this angularly shaped rod is to secure the spray deflecting

lip to the sprinkler by means of a flexible connection thus allowing it to assume an inoperative position, and to not interfere with the ordinary working of the sprinkler. 60

The spray deflecting member 8 is held in operative position on the sprinkler head 5 by means of a spring member 12 which is shaped to conform with the outer lower portion 8' of such spray deflecting lip. The construction is such that the lower portion 8' of the spray deflecting lip will slide in operative position between such spring member 12 and the sprinkler head 5 and be frictionally maintained therebetween. Said 70 spring member is provided with an ear 13 secured to the sprinkler by means of a rivet or screw 14. The upper portion of the spray deflecting lip has its central portion curved slightly over the sprinkler head 2 in 75 order to curve the spray from its regular course and cause it to be deposited on surfaces upon which some of the rest of the spray is falling. The end parts of such end portions are bent outwardly in a substantially tangential plane with the sprinkler head 5 as clearly illustrated.

In use, when it is not desired to use the spray deflecting lip the same is disengaged from the position shown in Fig. 2 and allowed to rest on the base portion 6 so that it will not interfere with the regular working of the sprinkler. When it is desired to use the spray deflector, ear 9 is slid on the angular rod 10 to substantially the position shown in Fig. 2 and its lower portion 8' inserted between the flexible member 12 and sprinkler head 5, the sprinkler may then be placed near the walk or other object on which it is desired to prevent the 95 spray from falling and connected with a source of water supply in the usual manner. The portion of the spray coming from the orifice 15 and engaging the deflector lip 8 will be diverted from its regular course and fall with the balance of the spray coming from such orifice and leave the walk or other object entirely dry. In this manner the sprinkler will spray a surface close to a walk or other object without spraying such 105 walk or other object as is the usual case with the conventional sprinkler.

While I have illustrated and described the preferred form of construction for carrying my invention into effect, this is capable of 110 variation and modification without departing from the spirit of the invention. I,

therefore, do not wish to be limited to the precise details as set forth, but desire to avail myself of such variations and modifications as come within the scope of the appended claims.

Having described my invention what I claim as new and desire to secure by Letters Patent is:

1. In combination, a sprinkler head provided with a lateral flange; an angular rod having one end secured on said sprinkler and a head on its free end; a spray deflecting lip having its lower surface engaging the side of the head of said sprinkler and supported on said flange and provided with an ear slidably mounted on said angular rod; and a resilient member carried by said sprinkler with its inner surface conforming with the lower outside surface of said spray deflecting lip for maintaining said deflecting lip in operative position on said sprinkler, substantially as described.
2. In combination, a sprinkler head hav-

ing a lateral flange; an angular rod having one end secured on said sprinkler and a head on its free end; a spray deflecting lip having its lower inner surface conforming with the side of the head of said sprinkler and provided with an ear slidably mounted on said angular rod, the upper portion of such spray deflecting lip having its central part curved over said sprinkler head and the lower end thereof resting on said lateral flange; and a curved spring member carried by said sprinkler and adapted to engage the lower portion of said spray deflecting lip to maintain the same in operative position on said sprinkler, substantially as described.

In testimony whereof I have signed my name to this specification in the presence of two subscribing witnesses.

EMIL E. HANSEN.
